THREAD CONTROLLING AND SEVERING
MECHANISM FOR SEWING MACHINESMichael McCann, Ozone Park, N. Y., assignor to
The Singer Manufacturing Company, Elizabeth, N. J., a corporation of New Jersey

Application June 23, 1942, Serial No. 448,062

5 Claims. (Cl. 112—252)

This invention relates to sewing machines and more particularly to means for breaking the sewing thread at the completion of a sewing operation.

It is old and well known, in tacking and article attaching machines, as shown, for example in U. S. patent to Lyons, No. 1,018,201, Feb. 20, 1912, to break the sewing thread, at the completion of a sewing cycle, by raising the work-clamp and the work supported thereby while the last thread-loop is retained by the loop-taker.

This means of severing sewing threads has, however, been ineffective when sewing with thread having a substantial amount of elasticity such, for example, as "nylon" thread. This is because of the fact that, during upward movement of the work-clamp (which movement is limited), the thread will merely stretch and will not be broken.

The present invention has as its primary object to provide means for taking substantially all of the stretch out of that portion of the elastic sewing thread adjacent the stitch-forming mechanism so that the thread may be broken by the normal lifting movement of the work-clamp.

A further object of the invention is to provide means cooperating with and actuated by the clamp-lifting mechanism of a sewing machine for first clamping the thread between the stitch forming mechanism and the source of supply and thereafter taking out of that portion of the thread adjacent the stitch-forming mechanism substantially all of the stretch therein so that normal lifting of the work-clamp will break the thread.

With the above and other objects in view as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a side elevation of a tacking machine embodying the present invention.

Fig. 2 is a vertical sectional view substantially on the line 2—2 of Fig. 1.

Fig. 3 is a fragmentary left end elevation, partly in section, of the machine shown in Fig. 1 showing the work-clamp in operative position.

Fig. 4 is a fragmentary view similar to the lower portion of Fig. 3 but showing the work-clamp raised to break the thread.

Fig. 5 is a vertical section substantially on the line 5—5 of Fig. 3 but with the work-clamp and the parts connected therewith raised to the position shown in Fig. 4.

5 Fig. 6 is a disassembled perspective view of a presser-foot supporting frame and a carrying bracket therefor, later to be described.

Referring more specifically to the drawings, the invention is disclosed as embodied in a tacking machine adapted particularly for tacking bands and bows on men's hats. The machine comprises essentially a base 1 having a forwardly extending cylindrical work-supporting bed 2 in which is journaled a rotary looper shaft

10 3 carrying, at its forward end a rotary chain-stitch looper 4. Secured upon the base 1 is a bracket-arm comprising a standard 5, and an overhanging arm 6 which terminates in a head 7 in which is mounted, for vertical reciprocation, a

15 needle-bar 8 carrying, at its lower end, an eye-pointed needle 9 which cooperates with the looper 4 in the formation of stitches. A face-plate 7a is secured to and forms a part of the head 7. A main or power shaft 10 is journaled lengthwise

20 within the arm 6 and carries, at its rear end, loose and tight pulleys 11 and 12, respectively. A driving belt (not shown) normally running on the loose pulley, is adapted to be shifted to the tight pulley when it is desired to operate the

25 machine. At its forward end, the shaft 10 is connected, by mechanism not shown, to reciprocate the needle-bar. The looper shaft 3 is driven from the main shaft through the medium of a pair of bevel gears 13 and 14, a vertically disposed

30 shaft 15, journaled in the standard 5, and a second pair of bevel gears 16 and 17 in the base 1. Starting and stopping of the machine is controlled by a conventional stop-motion designated generally as S.

35 40 A throat-plate 18 is secured upon the forward end of the bed 2 and is provided with a needle-hole 19 through which the eye-pointed end of the needle 9 passes for cooperation with the looper.

Work w to be stitched is carried by a work-clamp comprising a clamp base-plate 20 slidingly mounted, for sidewise movements, on the upper surface of the work-supporting bed 2 and actuated through mechanism designated generally as

45 x from a cycle-control cam-wheel 21 mounted on a shaft 22 journaled horizontally in the standard 5 and rotated from the main shaft by a worm 23 and worm-wheel 24, all as is common in this type of sewing machine. The work-clamp also

50 55 includes a work-supporting plate 25 which overlies the throat-plate and which is connected to

the forward end of an arm 26 pivoted at 27 to the base of a bracket 28 secured upon the clamp base-plate 20. Cooperating with the plate 25 in holding the work, is a pair of spaced presser-feet 29 which are pivotally mounted, as by shoulder screws 30, upon a frame 31 which, in turn, is pivotally mounted in a U-shaped bracket 33 by shoulder screws 32. This bracket is secured upon the lower end of a spring-depressed presser-bar 34, mounted for endwise movement in the bracket-arm head 7. The presser-feet 29 are normally held in the operative position shown in full lines in Fig. 1 and in Fig. 5 by a spring 35 carried by the frame 31, but the feet may be swung to the inoperative position, indicated in dotted lines in Fig. 1, to facilitate threading of the needle.

During the tacking operation, the work-supporting plate 25 and the work supported thereon are shifted laterally between successive reciprocations of the needle, thereby to cause the needle to penetrate the work alternately at two laterally spaced points. During this lateral shifting of the work, the frame 31 and the presser-feet 29 swing back and forth therewith about the axes of the pivot screws 32, while holding the work depressed upon the plate 25. A coil spring 36, surrounding one of the screws 32 and having two outwardly extending arms 36^a and 36^b, of which the former engages the frame 31 while the latter engages the upper edge of the bracket 33, normally maintains the frame 31 and the presser-feet carried thereby in one extreme position but permits them to be swung laterally therefrom by the work-shifting movement of the work-supporting plate 25.

The presser-bar 34 and the presser-feet carried thereby may be raised, to permit insertion and removal of the work, by means of a manually actuatable lever 37 fulcrumed at 38, on a bracket 39 secured upon the upper side of the overhanging arm 6. The forward end of the lever is forked and embraces the presser-bar beneath a collar 40 secured to the upper end of the presser-bar. The opposite end of the lever is connected, as by a chain 41, to any suitable lifting treadle.

Pivotedly connected, by a screw 42, to the lever 37, forwardly of the fulcrum 38, is the upper end of a two-part link 43 of which the lower part 43^a is formed with a hook portion 44 adapted to engage beneath a block 45 adjustably secured to an arm 47 projecting upwardly from the arm 26.

After the machine has been brought to rest at the end of the stitching cycle the lever 37 is swung clockwise, as viewed in Fig. 1, to lift the presser-feet whereupon the hook-portion 44 of the link 43 engages beneath the block 45 and lifts the work-supporting plate about its pivot 27 (as indicated in dotted lines in Fig. 1) thereby breaking the sewing thread, as is well understood. The lower part 43^a of the link 43 passes through the bifurcated end 28^a of the bracket 28 and is formed with a cam portion 48 which, during upward movement of the link, engages a stud 49 carried by bracket, thereby causing the link to be shifted laterally to the position shown in dotted lines in Fig. 1. This causes the hook portion 44 to be disengaged from the block 45 whereupon the work-supporting plate 25 falls to the position shown in full lines in Fig. 1, for the next operation. A spring 90 surrounding the pivot screw 42 and having arms 91 and 92 engaging, respectively, the lever 37 and the link 43 holds the lower end of said link in contact with the stud 49 and constantly tends to maintain the hook 44 beneath the block 45.

The sewing thread *t* extends from a source of supply through tensions T and T¹, thread guides 50 and 51 carried by the head 7 and needle-bar, respectively, thence downwardly and through a thread-check 52, through a thread-eye 53 formed in a plate 54 adjustably mounted on the face plate 7^a, and thence through a thread-eye 55 formed in an upstanding arm 31^a constituting a part of the frame 31. From the thread-eye 55 the thread extends to the eye of the needle. The thread-guide 51 is carried by the upper end of the needle-bar 8 and, in conjunction with the stationary thread-guide 50, acts as a take-up mechanism to set a stitch upon each upward movement of the needle-bar. This take-up mechanism forms no part of a thread-stretching device hereinafter to be described.

Intermediate the tension T¹ and the thread-guide 50 there is arranged a thread restraining means or thread-clamp designed to grip the thread at the completion of the sewing cycle to prevent thread from being drawn from the supply by the thread-breaking operation later to be described. This thread-clamp comprises a pair of thread-guides 56, secured by a bolt 57 to a bracket 58 fixed upon the arm 6. The head 57^a of the bolt 57 underlies the thread *t* and forms a fixed thread-clamping jaw. Cooperating with the fixed jaw is a movable thread-clamping jaw consisting of the forward end 59^a of a thread-clamping lever 59 fulcrumed, at 60, on the bracket 58. The rear end of the lever 59 is connected, at 61, to a thread-clamp actuating rod 62, the lower end of which is slidably connected to one arm 63^a of a bell-crank lever 63, fulcrumed at 64 to the bracket 58. A collar 65 is secured upon the rod 62 and a coil spring 66 is interposed between the collar and the arm 63^a. The other arm 63^b of the lever 63 carries a round-headed stud 67 adapted, near the end of the stitching cycle, to be engaged by one of a plurality of cam plates 68 carried by the cam-wheel 21. Engagement of the cam-plates 68 with the stud 67 causes the bell-crank lever 63 to be turned clockwise, as viewed in Fig. 1, thereby, through the spring 66, collar 65, and rod 62 turning the lever 59 clockwise, as seen in Fig. 2, and causing the thread to be gripped between the end 59^a of the lever 59 and the bolt head 57^a. Thus the machine is brought to rest, at the completion of a sewing cycle, with the thread clamped by the thread-clamp and stretched taut by the take-up 50, 51.

To insure that ample thread will be provided for making the first stitch of the next succeeding cycle, means is provided for pulling off a length of thread from the supply and through the tensions T and T¹ by the lifting of the work-clamp. This means comprises a lever 69, fulcrumed, at 70, to the bracket 58 and carrying, at its upper end a thread-engaging wire loop 71 which is located between the thread-clamp and the tension T¹ and through which the thread passes. The lever 69 is connected with the lever 37, to be actuated thereby, by a link 72 having its upper end connected at 73 to the lever 37 and its lower end, at 74, to the lever 69. Thus, as the lever 37 is actuated to lift the presser-feet and work-clamp the lever 69 is rocked counter-clockwise, as seen in Fig. 2, causing the loop 71 to draw thread from the supply.

The rear end of the lever 37 is normally maintained elevated by a coil spring 75, surrounding a rod 76 connected to the lever 37 rearwardly of its fulcrum 38 and maintained between a

bracket 77, secured to the bracket 58, and a collar 78 fixed to the rod 76.

At the end of a stitching cycle, the machine comes to rest with the parts in the position shown in Figs. 1 and 3; i. e. with the thread-clamp 57^a, 59^a closed; with the work-clamp in its lowermost position; with the looper holding the last thread-loop; and with the thread taut and inclined downwardly through the thread-eyes 53 and 55. Thereafter the operator actuates a suitable treadle (not shown) thereby turning the lever 37 clockwise, as viewed in Fig. 1. As hereinbefore stated, this lifts the presser-bar 34 and the presser-feet carried thereby and also lifts the work-clamp from the operative position shown in Fig. 3, and in full lines in Fig. 1, to the position shown in Figs. 4 and 5, and in dotted lines in Fig. 1.

When sewing with cotton or silk thread, which have relatively little elasticity, this upward movement of the work-clamp and the work carried thereby relative to the looper causes the work-limb of the thread-loop held by the looper to be broken adjacent the work. However, when sewing with thread having a substantial amount of elasticity, such for example as "nylon" thread there is sufficient stretch in the thread that the work-clamp may be raised without breaking the thread, the thread merely stretching.

To overcome this condition and to insure that "nylon" and similar threads will be broken by the raising of the work-clamp, this invention provides means, operable during the lifting of the work-clamp, for taking out a substantial amount of the stretch in that portion of the thread adjacent the stitch-forming mechanism. This is effected by relative movement of the thread-eyes 53 and 55. As shown in Figs. 1 and 3 during the sewing operation and until the work-clamp is raised the taut thread extends diagonally downwardly through the thread-eyes 53 and 55. When, however, the presser-feet (and therewith the work-clamp) are raised the eye 55 in the arm 31^a is raised relative to and above the stationary eye 53. This snubs the taut thread about the upper wall of the thread-eye 53 and forms a bight b therein, as shown in Figs. 4 and 5. The formation of the bight in the thread requires an additional length of thread which is supplied by the stretching of the thread between the thread-eye 53 and the last stitch anchored in the work, including the loop-retained by the looper. After a substantial portion of the stretch in the thread has been taken out, continued upward movement of the work-clamp causes the limb of the thread-loop which is attached to the work to be broken close to the work, as indicated at f in Figs. 4 and 5, after which the free end e of the thread may be pulled out from the work as for example, by removing the work from the machine.

As shown most clearly in Figs. 3 and 5 the plate 54, in which the thread-eye 53 is formed, is adjustably secured, by screw 80, to the face-plate 7^a. Thus by vertical adjustment of the plate 54 the relation of the thread-eyes 53 and 55 may be varied, whereby the length of the thread forming the bight b may also be varied, thereby to take out more or less stretch in the sewing thread.

From the foregoing it will be apparent that this invention has provided positive yet simple means operative by and during the lifting of the work-clamp first to take stretch out of a sewing thread adjacent the stitch-forming mechanism,

and thereafter to break the thread, as is common in this type of sewing machine.

Having thus set forth the nature of the invention, what I claim herein is:

- 5 1. In a cyclically operated sewing machine having a head, a work-clamp, a presser-bar, and stitch-forming mechanism including a thread-carrying needle and a cooperating looper which retains a loop of the thread at the end of a stitch forming cycle; the improvement which consists in the provision of a stationary thread-eye carried by said head and a movable thread-eye carried by said presser-bar through which thread-eyes the thread passes in its movement
- 10 15 from a source of supply to said stitch-forming mechanism, means to clamp the thread between said source of supply and said thread-eyes, means operable while the thread is clamped and while a thread-loop is retained by said looper to lift said presser-bar and to shift said movable thread-eye relative to said stationary thread-eye to form a bight in the thread thereby to stretch said thread and render it comparatively inelastic, and means to lift said work-clamp to strain the stretched thread to cause breakage thereof.
- 20 25 2. In a cyclically operated sewing machine as set forth in claim 1, in which one of the thread-eyes is adjustable with respect to the other thread-eye thereby to vary the amount of stretching action that will be imposed upon the thread by a unit movement of said movable thread-eye.
- 30 35 3. A sewing machine comprising a vertically movable work-clamp, stitch-forming mechanism including a reciprocating needle and a cooperating looper adapted to form stitches in a work-piece held by said work-clamp with a thread having a substantial amount of elasticity, automatically actuated means for clamping the thread before the machine is brought to rest at the completion of a sewing cycle to prevent thread being drawn from the supply, means for lifting said work-clamp at the completion of a sewing cycle and with the last thread-loop held by the looper, thread-snubbing means adjacent the needle and rendered effective by the initial movement of said work-clamp lifting means to snub the thread and simultaneously with said snubbing action to form a bight in that portion of the thread between the thread-snubbing means and the looper to take out of that portion of the thread a substantial portion of its elasticity, whereupon further upward movement of the work-clamp and work-piece carried thereby strains the stretched thread and causes breakage thereof adjacent the work-piece.
- 40 45 50 55 4. A cyclically operated sewing machine comprising stitch-forming devices including a needle and a cooperating looper for forming stitches, normally ineffective thread restraining means located between the source of thread supply and said stitch-forming devices, automatically actuated means rendering said thread restraining means effective before the machine is brought to rest to prevent thread from being drawn from the supply, means acting on the thread between said restraining means and said needle to snub the thread and simultaneously therewith to stretch that portion thereof between the snubbing means and the underside of the work, thereby to take out a substantial portion of its elasticity, and means for straining the stretched thread to cause breakage thereof.
- 60 65 70 75 5. A sewing machine comprising stitch-forming devices for forming groups of stitches, means for bringing the machine to rest after the com-

pletion of a group of stitches, a normally ineffective thread-restraining means located between the source of thread supply and said stitch-forming devices, means actuated automatically near the completion of a group of stitches to render said thread-restraining means effective to prevent drawing of thread therethrough, means acting on the thread between said restraining means and

said stitches, after the machine has been brought to rest, to stretch that portion of the thread adjacent the stitch-forming devices thereby to take out a substantial portion of its elasticity, and means for straining the stretched thread to cause breakage thereof.

MICHAEL McCANN.
